UNITED STATES PATENT OFFICE

HENRY L. ELLIOTT AND ROBERT A. CARROLL, OF CLAYSVILLE, PENNSYLVANIA, AS
SIGNORS OF ONE-THIRD TO THOMAS W. HENDERSON, OF WASHINGTON, PENN-
SYLVANIA.

VENTILATING APPARATUS

Application filed April 13, 1929. Serial No. 354,781.

Our invention relates to certain new and useful improvements in ventilating apparatus, and important objects of the invention are to provide a ventilating apparatus of the character described, in a manner as herein-after referred to, which is adapted for connection and operation in conjunction with the heating system of the structure to be ventilated; which may be readily connected in a heating system already installed, as well as form a component part of the heating system; and which will function effectively to purify cool and circulate the air within the structure equipped therewith.

Further objects of the invention are to provide a device of the class stated which is simple in its construction and arrangement, durable and efficient in its use, compact, automatic in its operation, positive in its action, and comparatively economical in its manufacture, installation, operation and maintenance.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:—

Figure 1 is a vertical cross sectional view of a ventilating unit, constructed in accordance with the invention and adapted for connection with a hot air type of heating system.

Figure 2 is a top plan view thereof.

Figure 3 is a side view of a modified form of ventilating unit adapted for connection with heating systems employing water, steam, vapor or the like as a heating agent.

Referring in detail to the drawing our im-

proved ventilating apparatus comprises a receptacle 1 provided with an open top which is closed by a removable, air-tight cover 2. The interior of the receptacle 1 is divided into a primary chamber 3 and a secondary chamber 4, by a partition wall 5, which is disposed transversely and extends vertically. The partition wall 5 is fixed to the bottom and side walls of the receptacle 1 and the upper end thereof projects into a hood 6, which is fixed to the top of the cover 2. The only communication between the primary and secondary chambers 3 and 4 is through the hood 6 over the upper end of the partition wall 5, which is spaced from the top of the hood 6 to provide a passage therebetween.

A primary cooling coil 7 is mounted in the primary chamber 3 and a similar cooling coil 8 is mounted in the secondary chamber 4. The inlet ends of the cooling coils 7 and 8 connect and communicate with a common inlet conduit 9 and are provided with respective control valves 10 and 11. The outlet ends of the cooling coils 7 and 8 connect and communicate with the outlet conduit 12, as indicated at 13.

The inlet and outlet conduits 9 and 12 are adapted for connection with any suitable mechanical refrigerating unit of the type now in common use for cooling associated coils to a desired low temperature for refrigerating purposes. No claim is made to any particular mechanical refrigerating unit except for the specific arrangement of the associated coils 7 and 8 as embodied in the present invention.

A plurality of spaced, transversely extending and vertically disposed baffle plates 14 are fixedly carried by the cover 2 and depend into respective chambers 3 and 4. A plurality of similarly disposed baffle plates 15 are fixed to the bottom of the receptacle 1.

The baffle plates 14 and 15 are disposed in staggered relation with respect to each other, and extend into the bends forming respective cooling coils 7 and 8, the lower ends of the

baffle plates 14 being spaced from the bottom of the receptacle 1 and the upper ends of the baffle plates 15 being spaced from the cover 2.

The primary chamber 3 carries a supply of liquid 16, preferably water mixed with some suitable, non-corrosive chemical agent to prevent the possibility of freezing the water by the temperature of the primary coil 7, which has the greater portion thereof submerged in the liquid 16.

The cover 2 is provided with an inlet plug 17 for supplying or replenishing the liquid 16 in the primary chamber 3. The receptacle 1 carries a gauge 18 which registers the level 15 of the liquid 16, and embodies a drain valve 18' for draining the liquid 16 from the primary chamber 3 when required. The baffle plates 15 in the primary chamber 3 are formed with apertures 19, which are disposed adjacent to the bottom of the receptacle 1, and provided to allow the draining of the chamber 3, in the manner herein stated.

No liquid is carried in the chamber 4, and the secondary coil 8 in the latter virtually constitutes a condenser for dehydrating the air on its passage through the said chamber 4. A cup 20, provided with a drain cock 21, is fixed to the bottom of the receptacle 1 and communicates with the chamber 4 for collecting potential drippings from the operation of the condenser coil 8. The baffle plates 15 in the secondary chamber 4 are formed with apertures 22, which are disposed adjacent to the bottom of the receptacle 1 to permit the draining of the chamber 4 of dripping, as herein set forth.

Figure 2 illustrates the embodiment of our improved ventilating apparatus as functioning through a hot air type of heating furnace. An air outlet conduit 23 establishes communication between the secondary chamber 4 and the distributing dome 24 of any ordinary hot air type of heating furnace. The outlet conduit 23 connects with the cover 2 and communicates with the chamber 4 at a point between the end wall of the receptacle 1 and the baffle plate 14 which is adjacent to said end wall.

Air is supplied to the ventilating apparatus through an inlet conduit 25 which connects with the cover 2 and communicates with the primary chamber 3 at a point between the other end wall of the receptacle 1 and the baffle plate 14 which is adjacent to said end wall.

The air is driven through the ventilating apparatus by a power operated blower 26, as shown, which is connected with the inlet conduit 25. It will, of course, be obvious that the latter may connect with an air storage reservoir providing the desired air pressure to operate the ventilating apparatus, instead of employing the blower 26, as stated. The air supply may be drawn from the enclosures be-

ing ventilated or from a fresh source of supply.

In practice the operation of our improved ventilating apparatus, when used in connection with a hot air type of heating system, is as follows:—The operation of the blower 26 will force the air into the primary chamber 3, through the liquid 16, downward and upward between the baffle plates 14 and 15 and along the entire length of the primary coil 7. As the temperature of the latter and of the liquid 16 is very low, the air on its passage through the primary chamber 3 in the manner stated, will become chilled. Further the forced passage of the air through the liquid 16 will remove all impurities therefrom.

The chilled air now passes from the primary chamber 3 through the hood 6 and over the top of the partition wall 5 into the secondary chamber 4. The air passes around the baffle plates 14 and 15 in the secondary chamber 4 and along the secondary coil 8, which still further chills the air to the temperature desired and prepares same for distribution. The air is now forced from the secondary chamber 4 into the furnace dome 24 through the outlet conduit 23. The chilled air is driven from the furnace dome 24 by its normal operating pressure and is distributed to the various rooms of the building structure through the usual warm air pipes connected with the furnace dome 24 in the manner identical to their function when employed for distributing hot air in the usual manner.

It will be apparent that the air may be distributed without utilizing the distributing ducts of a hot air heating system, by providing special distributing conduits therefor. However, the heat distributing ducts of a hot air heating system are admirably adapted for distributing the cool air as described. It is, of course, intended to operate the cooling and ventilating device only during the seasons in which the heating system is not required for heating purposes.

The control and operation of the secondary coil 8 regulates the humidity of the cooled air before the same is distributed. An excessive amount of moisture in the air might result in unhealthful conditions and dampness. It might also cause condensation on the interior of the distributing ducts, causing rust or corrosion.

Figure 3 illustrates a modified form of ventilating and cooling system which is designed for use in connection with a heating system employing water, vapor and the like through radiators in the usual manner.

The device comprises a cooling coil 27 mounted in a closed water receptacle 28. The coil 27 is identical in construction and operation as the primary coil 7, herein described, and is provided with an inlet connection 29, including a control valve 29', and with an

outlet connection 30. The receptacle 28 is also provided with a plurality of baffle plates 31, which are arranged in a manner identical to that described relatively to the preferred form.

5 A pump 32 is employed for circulating water through the receptacle 28 and through the radiators of the heating system with which the device is connected. A conduit 33 communicably connects the one end of the receptacle 28 with the pump 32, and a pipe 34 connects the latter with one end of the radiator installation. Another pipe 35 connects the other end of the radiator installation with the other end of the receptacle 28.

10 It will be evident that the operation of the pump 32 will continually circulate the water through the radiators and through the receptacle 28. The water, on passing through the receptacle 28, is chilled by cooling coil 27, whereby the radiators will be continuously filled with very cold circulating water providing the desired temperatures to the enclosures in which they are located.

15 The present invention provides a most efficient device of its kind for regulating and controlling ventilation to enclosures at any cooling temperature desired.

20 What we claim is:

1. In a ventilating apparatus of the character described, a closed receptacle, a partition wall dividing said receptacle into a primary chamber and a secondary chamber, 25 said chambers communicating with each other at the upper end of said partition wall, a primary cooling element mounted in said primary chamber, a secondary cooling element mounted in said secondary chamber, liquid stored in said primary chamber and partially submerging said primary element, means for forcing air under pressure through the liquid in said primary chamber and through said secondary chamber, a plurality of baffle plates fixed in said receptacle for directing the air against said cooling elements on its passage through said chambers, and means communicating with said secondary chamber and with the 30 heat distributing ducts of a hot air furnace for distributing the air from said receptacle through said ducts.

2. In a ventilating apparatus of the character described, a closed receptacle, a partition wall dividing said receptacle into a primary chamber and a secondary chamber, said chambers communicating with each other at the upper end of said partition wall, a primary cooling element mounted in said primary chamber, a secondary cooling element mounted in said secondary chamber, liquid stored in said primary chamber and partially submerging said primary element, means for forcing air under pressure 35 through the liquid in said primary chamber

and through said secondary chamber, a plurality of baffle plates fixed in said receptacle for directing the air against said cooling elements on its passage through said chambers, means communicating with said secondary chamber and with the heat distributing ducts of a hot air furnace for distributing the air from said receptacle through said ducts, and means for regulating the operations of said cooling elements.

70 In testimony whereof we affix our signatures.

HENRY L. ELLIOTT.
ROBERT A. CARROLL.
